UNITED STATES PATENT OFFICE.

ISAAC HIRSCH, OF CHICAGO, ILLINOIS.

DESIGN FOR A FORK.

SPECIFICATION forming part of Design No. 24,534, dated August 13, 1895.

Application filed May 1, 1895. Serial No. 547,806. Term of patent 3½ years.

To all whom it may concern:

Be it known that I, ISAAC HIRSCH, a citizen of the United States, residing at Chicago, in the county of Cook and State of Illinois, have 5 invented and produced a new and original Design for Forks, of which the following is a specification.

My design relates to forks.

Figure 1 is a plan view of a fork, showing 10 my design. Fig. 2 is a side elevation of the same.

The leading feature of my design consists 15 in a wire closed-loop handle at one end and an open loop at the other end, forming the tines, the two loops separated by twisting the two wires together.

A is the closed-loop handle. C is the open loop forming the tines of the fork, and B is the twisted portion separating the two loops. The open loop C is bent downwardly, as shown in Fig. 2, so as to be in a different plane from that of the loop A.

I claim—

The design for a fork herein shown and described.

ISAAC HIRSCH.
